Primary Examiner — Sharon S Oum(74) *Attorney, Agent, or Firm* — McGarry Bair PC**CLAIM**

The ornamental design for a ceiling fan blade iron, as shown and described.

DESCRIPTION

FIG. 1 is a bottom perspective view of a ceiling fan blade iron shown in the environment of a ceiling fan, showing my new design;

FIG. 2 is a top perspective view of the blade iron of FIG. 1, having the ceiling fan environment removed;

FIG. 3 is a left side view thereof;

FIG. 4 is a right side view thereof;

FIG. 5 is a top view thereof;

FIG. 6 is a bottom view thereof;

FIG. 7 is a rear view thereof; and,

FIG. 8 is a front view thereof.

The broken lines illustrate portions of the ceiling fan blade iron and ceiling fan environment that form no part of the claimed design.
